UNITED STATES PATENT OFFICE.

HAROLD O. HILL, OF ASPINWALL, AND WILLIAM WILKINSON, OF INGRAM, PENNSYLVANIA, ASSIGNORS TO RITER-CONLEY MANUFACTURING COMPANY, OF LEETSDALE, PENNSYLVANIA, A CORPORATION OF PENNSYLVANIA.

TOWER CONSTRUCTION.

Application filed July 19, 1922. Serial No. 576,017.

To all whom it may concern:

Be it known that we, HAROLD O. HILL and WILLIAM WILKINSON, citizens of the United States, residing at Aspinwall and Ingram, respectively, in the county of Allegheny and State of Pennsylvania, have invented certain new and useful Improvements in Tower Constructions, of which the following is a specification.

10 This invention is for an improvement in structural towers of the type used in supporting high tension transmission lines, telegraph, or telephone lines, radio antenna, and for similar purposes, and relates particularly to a ground anchor for such towers.

Heretofore, two methods of erecting such towers have been employed. The first method is to provide four concrete bases to which the legs of the tower are secured.

20 The second method is to employ structural metal anchors in the ground, to which the legs of the tower are secured. The present invention pertains to the latter method.

One of the earliest and most commonly used methods is the provision of a stub formed of an angle iron connected at its lower end to a grillage of crossed metal members embedded in the earth. The top of the stub, one being employed for each leg of the tower, projects just a few inches above the ground line. At a sufficient distance below the surface of the ground, transverse metal channels of short length, known as "shear channels," were secured to the stubs, one at right angles to the other, to give the stub a sufficient resistance surface to movement in the ground to withstand lateral strains. This is a highly desirable arrangement because, when the towers are constructed, they are completely assembled on the ground, then raised to a vertical position. The stubs could be set by a separate crew of workmen in advance of the erection of the tower, and, if the stubs did not correspond to the exact position of the legs, they could be flexed sufficiently to bring them into position.

With the increase in the length of spans, the size and weight of towers and transmission lines, it has been found, however, that the stubs will bend or break between the ground line and the shear channels when

the tower is subjected to certain strains, particularly high winds. This is due to the strains transmitted to the upper ends of the 55 stubs through the lowermost diagonals of the tower.

It has been proposed to remedy this defect by having three or more stubs or angle bars connected to a grillage in the ground 60 at each corner, instead of one. This is objectionable in that, if the anchor structure at each corner is not accurately positioned, it is almost impossible to flex it around into proper position. Furthermore, if the grillage is not set in the ground level, the three 65 angle bars do not receive the load equally.

Another method of construction proposes to connect the diagonals of the tower to the stubs below the ground line. Such an arrangement, while effective, requires considerably more excavating than the method first described, and requires that the tower be erected before the diagonals are connected with a bracing structure, so that the tower 70 is more or less flimsy while being raised. Further disadvantage resides in the necessity for flexing three different members of each stub into position with three corresponding members at each corner of the 75 tower. As the diagonals are of lighter stock than the legs of the tower, they rust through more rapidly, and being underground, they 80 may get in an unsafe condition without the line inspector being able to discover it. 85

The present invention proposes to utilize the advantages of the first of the three stub arrangements just described, but to provide means on the stub member capable of withstanding bending moments transmitted 90 through the diagonals of the tower.

Our invention may be readily understood by reference to the accompanying drawings, in which:

Fig. 1 is a side view of a stub in position, 95 showing one leg and the diagonal of the tower attached thereto;

Fig. 2 is a section on line II—II of Fig. 1;

Fig. 3 is a section on line III—III of Fig. 1;

Fig. 4 is a side elevation of a complete tower;

Fig. 5 is a view similar to Fig. 1 of a slight modification;

Fig. 6 is a section on line VI—VI of Fig. 5;

Fig. 7 is a view similar to Fig. 1 of another modification; and

5 Fig. 8 is a cross section on line VIII—VIII of Fig. 7.

In the drawings, A represents a structural tower having legs 5 and diagonals 6 which connect on to the extreme lower ends 10 of the legs. The legs themselves terminate above the ground line, indicated at G—G.

The stub construction, one of which is used for each leg of the tower, and which is often set in the ground sometime previous 15 to the erection of the tower, is designated generally as B.

It comprises a grillage 7 of any usual or preferred construction. The grillage shown in the drawings is formed of a plurality of 20 cross ties 8 tied together at their ends by angle bars 9, and to which are secured parallel channel beams 10. Between these channel beams 10 is secured a vertical section of I-beam 11, to which the stub 12 is fastened.

25 The stub 12 comprises an angle bar of sufficient strength and of the necessary length to enable the grillage to be buried far enough under ground to get the desired anchoring, and yet normally provide for an end projecting above the ground line.

30 So much of the construction as described is old in the art. The present invention is for the purpose of improving this construction to prevent the stub 12 from breaking 35 at or near the ground line. It has generally been the practice to secure two shear-channels to the stub at the necessary distance below the ground line for the purpose of giving added surface to resist movement 40 of the stub in the earth, but these may be omitted in the present case.

45 Secured to the stub as shown in Fig. 1, a short distance below its upper end, is a longitudinal angular member 13 preferably in the form of a Z-bar, or similar form, having more than a single angle therein. This bar 13 is of sufficient length to extend 50 well down into the ground. The web of the bar secured to the stub resists strain in one direction and the intermediate web of the bar resists bending moments in a direction at right angles thereto, so that the stub is securely braced against lateral bends, due 55 to the horizontal components of the strain transmitted thereto, through diagonals extending in either of two directions from the stub.

60 The intermediate and the third face of the bar, beside adding greatly to the strength of the stub, increases the area of contact with the earth, so that the strain is diffused through a greater surface of earth, and consequently, the earth can resist greater strains without yielding.

65 In Figs. 5 and 6, we have shown two such

angular members, designated 13^a, which give greater strength to the stub and greater area of contact with the earth.

In Figs. 7 and 8, the arrangement is similar to that shown in Figs. 1 and 2, but the 70 angular member or Z-bar 13^b extends to the top of the stub. In order that it may do this, a filler strip 14 is placed between the attaching web of the bar and the stub, which filler extends up to the point where the 75 splice between the stub and the leg commences, the upper terminal of the filler being designated at c. The advantage of this construction is to enable the diagonal to be attached to the leg at a point just above the 80 splice, so that if the tower is assembled on the ground before being raised, the diagonals may be permanently attached to the leg, thus facilitating the erection of the 85 tower while ensuring sufficient strength to the stub above the ground line and below the end of the diagonal.

When erecting the towers, particularly in isolated territory, the stubs constructed in accordance with our invention may be permanently positioned in the ground. The towers, which are ordinarily fabricated in the shops, are shipped in pieces to the point where they are to be erected. The towers may be built up from the stubs, or assembled on the ground and raised to vertical 90 position afterwards. In either event, the stubs may be flexed or sprung sufficiently so that if not accurately set in the beginning, they can be brought into place without difficulty.

95 The reinforcing angular members brace the stub where it meets the greatest horizontal strain, and transmits such lateral components well down into the ground, while the added lateral bearing surface, gained by the angular members, distributes these strains into the ground below the surface where the earth is sufficiently compact to 100 resist the horizontal shear, and diffuse the strain so that the earth may withstand more strain.

105 Various changes and modifications may be made in the construction, particularly in the shape of the angular members for bracing the stubs, within the contemplation of our invention and within the scope of the 110 appended claims.

115 What we claim is:

120 1. A stub for tower constructions comprising a structural member having anchoring means at its lower end, and a reinforcing longitudinally extending member secured to the upper portion of said stub and extending well down toward the center thereof, said member having means for resisting strains in different directions and giving added surface to the stub for resisting movement in the earth.

125 2. A stub construction for towers com-

prising a structural member adapted to be partially embedded in the ground having anchoring means at its lower end, and longitudinally extending means on said stub member near the upper end thereof having a plurality of angularly disposed webs for bracing the stub against lateral strains, said means also providing added surface for contact with the earth to offer greater resistance to the movement of said stub when in the ground.

3. A stub construction for towers comprising a structural metal stub member adapted to be embedded in the earth, means for anchoring said member in the earth, and a longitudinally extending angular member secured to said stub near the upper part thereof and extending a considerable distance downwardly therealong, said angular member providing webs for resisting lateral strains in different directions and giving added surface to the stub for resisting movement in the earth.

4. A stub construction for towers comprising a structural metal stub member adapted to be embedded in the earth, means for anchoring said member in the earth, and a longitudinally extending angular member having a plurality of angles therein secured to said stub near the upper part thereof and extending a considerable distance downwardly therealong, said angular member providing webs for resisting lateral strains in different directions and giving added surface to the stub for resisting movement in the earth.

5. A stub construction for towers comprising a structural stub member adapted to be embedded in the earth, means for anchoring said member in the earth, and bracing means for the upper end of the stub comprising a longitudinally extending Z-bar secured to the stub.

6. A stub construction for towers comprising a structural stub member adapted to be embedded in the earth, means for anchoring said member in the earth, and bracing means for the upper end of the stub com-

prising a plurality of longitudinally extending Z-bars rigidly secured to the stub.

7. The combination with a tower having legs and diagonal braces secured to the lower ends of the legs, of ground stubs to which said legs are secured, said stubs comprising a stub member adapted to be embedded into the ground up to a few inches of its top, an anchoring means at the lower end of the stub member, and bracing means comprising a Z-bar secured to the upper part of said stub and extending from the splice between the leg and the stub a considerable distance into the ground.

8. The combination with a tower having legs and diagonal braces secured to the lower ends of the legs, of ground stubs to which said legs are secured, said stubs comprising a stub member adapted to be embedded into the ground up to a few inches of its top, an anchoring means at the lower end of the stub member, a Z-bar secured to the stub member and extending from the top of said stub member well down into the ground, said Z-bar overlapping the leg of the tower where it is spliced to the stub, and a filler interposed between the Z-bar and stub member below the leg, whereby the Z-bar may have a maximum strengthening effect.

9. The combination with a tower having legs and diagonal braces secured to the lower ends of the legs, of ground stubs to which said legs are secured, said stubs comprising a stub member adapted to be embedded into the ground, an anchoring means at the lower end of the stub member and bracing means comprising an angular member secured to the upper part of said stub and extending longitudinally thereof for a considerable distance, said angular member having means for resisting strains in different directions and giving added surfaces to the stubs for resisting movement in the earth.

In testimony whereof we affix our signatures.

HAROLD O. HILL.
WILLIAM WILKINSON.
